U.S. Appl. No. 13/179,826, filed Jul. 5, 2012, Melsheimer et al.

Primary Examiner — Ian Simmons*Assistant Examiner* — Ieisha Price(74) *Attorney, Agent, or Firm* — Brinks Gilson & Lione(57) **CLAIM**

The ornamental design for a medical device delivery handle, as shown and described.

DESCRIPTION

FIG. 1 is a perspective view of a medical device delivery handle showing the new design;

FIG. 2 is a rear view thereof;

FIG. 3 is a front view thereof;

FIG. 4 is a top view thereof;

FIG. 5 is a bottom view thereof;

FIG. 6 is a left-side view thereof;

FIG. 7 is a right-side view thereof; and,

FIG. 8 is an alternative perspective view thereof, shown with additional features for environmental purposes only.

The broken lines in the drawings illustrate portions of the medical device delivery handle which form no part of the claimed design.

1 Claim, 5 Drawing Sheets(56)
